UNITED STATES PATENT OFFICE.

ALEXANDER WURTS, OF PITTSBURG, PENNSYLVANIA, ASSIGNOR TO THE
WESTINGHOUSE ELECTRIC COMPANY, OF SAME PLACE.

LIGHTNING-ARRESTER.

SPECIFICATION forming part of Letters Patent No. 434,170, dated August 12, 1890.

Application filed May 15, 1890. Serial No. 351,961. (No model.)

To all whom it may concern:

Be it known that I, ALEXANDER WURTS, a citizen of the United States, residing in Pittsburgh, county of Allegheny, and State of Pennsylvania, have invented a certain new and useful Improvement in Lightning-Arresters, (Case No. 412,) of which the following is a specification.

The invention relates to the class of apparatus employed for affording a path to earth for lightning discharges which may traverse the main conductors of a system of electrical distribution, and also providing for the interruption of the flow of current to earth after the lightning has disappeared.

The present invention consists in providing a normally-broken path to the earth for one or both sides of the main-line circuit and in increasing the distance between the electrodes or terminals at the interrupted portion of the circuit by reason of the lightning discharge, and then causing the heat developed by the generated current passing across this space to still further increase the separation of the electrodes until the arc is completely interrupted.

The invention will be described in connection with the accompanying drawings, in which—

30 Figure 1 is a front elevation, partly in section, of an apparatus for carrying the invention into practice; and Fig. 2 is a side view thereof, also partly in section. These figures show the circuits in diagram.

35 Referring to the figures, A represents a dynamo-electric generator—such, for instance, as a source of alternating electric currents designed to supply arc lamps, such as indicated at B, which are connected in a main-line conductor L' L². The conductor L' is connected with the conductor c, leading through a support c' to a pivoted lever c². This lever carries an arm d', which projects through an aperture e' into the closed chamber E. The end of the arm d' approaches a conducting-electrode D, which is connected with the earth at G by the conductor c³. In like manner the line L² is connected by the conductor c⁴ with a support c⁵, and through it with a lever c⁶, carrying the arm d², which

also approaches the electrode D. The electrode D may be of any suitable conducting material. In practice carbon is found to serve the purpose very satisfactorily. The rods d' and d² may be of carbon or copper. 55 Excellent results are obtained with the latter. The electrode D may be turned to present fresh surfaces to the electrodes d' and d² when necessary. The short arms c⁷ of the levers c² and c⁶ extend beneath the end of a 60 flexible spring h, which is supported from the frame or base of the instrument. If the spring be forced down suddenly, it will strike against the ends of the arms and, turning the levers upon their pivots, carry the arms d' 65 and d² away from the electrode D, thus increasing the degree of separation. The arms d' d² are shown as being curved, so that they will move freely through the corresponding apertures when the levers swing upon their 70 pivots.

A solenoid K is connected in the main-line conductor—as, for instance, in the line L²—and this is provided with a movable core k, which when the current traverses the solenoid K is held up in the position shown in the drawings. When the current through the solenoid diminishes or ceases by reason of a short circuit to the earth through the electrode D, then the core is suddenly dropped, 80 striking upon the end of the spring h and causing the arms d' d² to be thrown away from the electrode D, as described. If therefore a current is passing to the earth through either arm d' or d² and the electrode D, the 85 arc will be drawn out by the separation of the electrodes, and the heat developed within the chamber E will be correspondingly increased and cause the expansion of the air within the chamber to such a degree as to force each arm 90 d' d² quickly out through the corresponding opening, thus completely interrupting the arc. The current will then be forced to flow through the solenoid K again, and the normal condition of the apparatus will be renewed. 95 If for any reason the current should fail to again flow through the solenoid K, the arms d' d² will still be allowed to return to their normal positions by reason of the spring h being sufficiently rigid to support the core 100

k free from the arms of the levers *c*² and *c*⁶. It will be understood that the resiliency of the spring is such as to permit it to be forced downward by reason of the momentum acquired by the core *k* when it drops suddenly from its solenoid *K*; but it will immediately return to its normal position, thus permitting the levers *c*² and *c*⁶ to return.

In some instances it may not be necessary 10 to employ the solenoid and core for giving the initial separation to the electrodes; but the heat developed by the original arc will be sufficient to cause the required separation.

It is evident that other details of construction 15 may be employed in place of those described; but that which I have already set forth will serve to clearly disclose the invention, its mode of operation, and apparatus for practicing the same. This form of lightning- 20 arrester is especially useful for alternating-current circuits where the heat developed at the arc between the lightning-electrodes may not be sufficient to force the rods *d*' and *d*² outward unless the degree of separation is 25 increased by mechanical means. At the same time the invention is applicable to circuits employing continuous currents.

In another application filed by me, Serial No. 351,523, I have described and claimed the 30 inclosing-case with its contained electrodes and supports.

I claim as my invention—

1. A lightning-arrester consisting of an electrode, a second electrode normally in proximity thereto and designed to be connected with the circuit to be protected, an electro-mechanical device for giving an initial separation of the electrodes brought into operation by variations in the current flowing 40 through the circuit, a chamber within which

the electrodes are inclosed, and an aperture through which one of said electrodes extends and within which it is movable.

2. The combination, with two normally-separated lightning-discharge electrodes, of a 45 chamber containing the same, one of the said electrodes being movable with reference to the other, and a device for giving an initial movement to the said movable electrode.

3. The combination, with two normally-separated lightning-discharge electrodes, of a 50 chamber containing the same, one of the said electrodes being movable with reference to the other, and a mechanical device for giving an initial movement to the said movable electrode, consisting of a solenoid and its core, 55 substantially as described.

4. The combination, with the electrode *D*, consisting of a ball of carbon or other conducting material, the lever *c*², the electrode 60 *d*', carried thereby, the chamber *E*, containing the said electrodes, a spring *h*, extending into proximity to said lever, a core *k*, and its solenoid *K*, all operating substantially as described.

5. In an apparatus for interrupting the flow 65 of electric currents, two separated electrodes, one movable with reference to the other, a chamber within which they are contained and through the walls of which one is movable under the influence of the expansion of the 70 air within the chamber, and a mechanical device for giving an initial movement to the movable electrode.

In testimony whereof I have hereunto subscribed my name this 13th day of May, A. D. 75 1890.

ALEXANDER WURTS.
